UNITED STATES PATENT OFFICE.

HYMAN HERMAN, OF TORONTO, ONTARIO, CANADA.

STOVE OR FURNACE.

1,256,798.

Specification of Letters Patent. Patented Feb. 19, 1918.

Application filed October 6, 1916. Serial No. 124,179.

To all whom it may concern:

Be it known that I, HYMAN HERMAN, a subject of the Czar of Russia, and resident of the city of Toronto, county of York, 5 Province of Ontario, in the Dominion of Canada, have invented certain new and useful Improvements in Stoves or Furnaces, as described in the following specification and illustrated in the accompanying drawings, 10 that form part of the same.

The principal objects of this invention are, to facilitate the proper cleaning out of the lower portion of a fire retaining the live coals securely within the fire pot and there- 15 by effecting a saving in fuel while obtaining the maximum efficient results from the fuel.

A further object is to reclaim the unburnt or partially unburnt coals without the usual attendant inconveniences of sifting ashes, 20 and to effectively prevent the escape of dust from the stove in the shaking of the grates.

The principal features of the invention consist in the novel construction and arrangement of parts, whereby supplementary 25 grate members are temporarily projected into the fire to sustain the upper portion of the fire while the grates are operated to release the lower portion and whereby the cinders are separated from the ashes coincident with the operation of the grates. 30

In the drawings, Figure 1 is a perspective view of a stove constructed in accordance with this invention having the forward portion of the outer casing surrounding the fire 35 box and ash pit removed.

Fig. 2 is an enlarged vertical cross sectional view through the fire box and ash pit showing the application of this invention.

Fig. 3 is a central longitudinal sectional 40 view of the fire box.

Like numerals of reference indicate corresponding parts in each figure.

In the use of ordinary forms of rocking, shaking or revolving grates the fire is entirely supported upon the moving grate members and when the grate members are turned a sufficient distance to allow partially burnt or dead coals, clinkers, etc., to pass through, a considerable quantity of live coals from the upper and active part of the fire are passed through with the others and the entire fire is disintegrated and a considerable percentage of dead material is still retained on top of the grates. 50

55 In the carrying out of the present invention I provide supplementary grate mem-

bers which are here shown as a plurality of curved fingers 1 connected together at their lower ends to the bars 2 and these bars are supported by the arms 3 secured to the shafts 60 4 extending longitudinally of the stove or furnace, below the fire box being journaled at the ends in suitable supports.

The side walls 5 of the fire box 6 are formed with perforations 7 through which 65 the upper ends of the curved fingers 1 extend and upon the rotation of the shafts 4 the fingers are projected inwardly into the fire box and meet centrally thereof to form a support for the upper portion of the fire. 70

The grate bars 8 which are here shown of the revolving type but which may be of any desirable form are journaled in suitable supports and in the usual manner and arranged at the bottom of the fire box and 75 below the path of the curved fingers 1 when said fingers are moved to their inner positions.

The grates are preferably operatively connected to operate in unison by means of the 80 gear wheels 9 and the shafts 4 supporting the curved fingers 1 are operatively connected at the ends by means of the gear segments 10 so that upon the operation of one of the shafts the other shaft will be 85 moved in unison therewith. One of the shafts 4 projects outwardly and is formed with a squared end to receive a shaker or operating lever as also is one of the grate bars 8. These shaker ends are adapted to 90 project through suitable openings in the outer casing of the stove closing in the fire box and ash pit.

When it is desired to clean out the lower portion of a fire, the shafts 4 are rotated to 95 move the curved fingers 1 upwardly and inwardly so that the ends project into the fire and meeting centrally provide a support for the upper portion. The shafts 4 may then be locked or they may be so designed to remain in their upward position without locking and while the fingers are in the raised position the grates 8 are operated to release the cinders, ashes and clinkers from the lower part of the fire box. These grates may be 100 operated to thoroughly clean out the lower portion of the fire and as the upper live portion of the fire is being sustained by the curved fingers 1, there will be no loss of the active portion. When the lower and burned 105 out portion of the fire has been cleaned the grates are adjusted to their normal position 110

and the curved fingers 1 are then withdrawn allowing the fire to settle down upon the grate surface. A completely fresh fire is thus obtained.

5 During the operation of shaking the ashes and cinders from the lower section of the fire the ashes in falling are intercepted by a sifter member 11 which is suspended at one end upon a rocking lever 12 and at the other 10 end upon a suitable pivotal support 13.

The lever 12 is pivoted intermediate of its length upon a cross bar 14 and the upper end is operatively connected with one of the operating gears 9 of the grate bars 8 through

15 a pivotal link 15, consequently as the grates are rocked or revolved the lever 12 is swung upon its pivot and the sifter member is oscillated. The sifter 11 is in the form of a pan with an open bottom having a screen 16 ex-

20 tending longitudinally thereof and sloping from the upper rear end to the lower forward end and an opening 17 is arranged at the forward end. The ashes are sifted through the screen and fall into an ash pan

25 18 arranged in the ash pit and the cinders roll down the inclined surface of the screen and pass through the opening 17 into the cinder pan 19. The partially burned portions of the fuel are thus saved and the pan may

30 be removed when desired. The ashes deposited in the ash pan are not disturbed but are removed in the pan, consequently the whole operation is rendered extremely cleanly.

35 In order to provide for the escape of the dust of the fine ash rising during the sifting or shaking operation, I provide a flue shown in dotted lines in Fig. 3 leading from the ash pit and connecting with the main smoke flue, a damper 20 is provided to close the 40 openings to this flue, except when the grates are being shaken.

The device is here shown as applied to a stove but it will be understood that the same 45 can be readily applied to a furnace. The necessary changes being only a matter of mechanical design.

What I claim as my invention is:—

1. In a stove or furnace, the combination with the firebox and grates, of a pair of 50 supplementary grate members pivotally supported below the firebox and having upwardly curved fingers adapted to be projected inwardly from each side of the firebox above the grates, and means for operating 55 said supplementary grate members in unison and independent of said grates.

2. A stove or furnace having the firebox formed with perforations in the side walls, shaking grates closing the bottom of the firebox, supplementary grates pivotally supported below the firebox at each side and having upwardly curved fingers adapted to be projected through said perforations into the firebox above the grates to support the 65 fire during the operation of the grates, means for operating said supplementary grates independent of the shaking grates to move inwardly and outwardly in unison.

3. In a stove or furnace, a firebox, grates 70 closing the bottom of the firebox, a pair of shafts journaled at the ends and extending longitudinally below the fire box, radial arms secured to said shafts, bars connecting the ends of said arms and having angularly disposed arc-shaped fingers arranged thereon and extending upwardly through the side walls of the firebox and adapted to project inwardly above the grates, means for shaking the grates, and means for operating 75 said supplementary grates in unison and independent of the main grates.

4. In a stove or furnace, in combination, a firebox, a shaking grate, means adapted to support the upper portion of the fire during 85 the operation of the shaking grate, a sifter supported at one end below the shaking grate upon a fixed pivot, a lever pivotally supported intermediate of its length and pivotally connected to the opposite end of 90 said sifter, and a link connecting the upper end of said lever to said shaking grates.

HYMAN HERMAN.
